UNITED STATES PATENT OFFICE

THOMAS BREDBURY, OF ANDOVER, MASSACHUSETTS, ASSIGNOR TO PATENT PROTECTION CORPORATION, TRUSTEE, OF LOWELL, MASSACHUSETTS, A CORPORATION OF MASSACHUSETTS

DEVICE FOR CLEANING GILL-BOX FALLERS

Application filed November 18, 1926. Serial No. 149,036.

This invention relates particularly to what are known as gill boxes used especially in the worsted industry for straightening wool fibers and laying them parallel.

Such gill boxes of the common type include two parallel top screws and under these two parallel bottom screws, so arranged in a frame and driven in such a manner that what are known as fallers, which are substantially rectangular bars of metal having one or more rows of pins projecting upwardly therefrom, will be caused to move in one direction between the top screws passing through the fiber and straightening it out until each one reaches the end of the top screws, when by means of suitable cams it is forced down in engagement with bottom screws by which it is carried back beneath the starting point, from whence it is lifted again to be engaged by the top screws and again carried forward.

It is found that the dirt and short fibers have a strong tendency to cling to each faller, and in fact wrap around it from the top to the bottom. As it is necessary to keep these fallers substantially clean, the machine must be stopped from time to time, usually several times a week, and as the fallers are quite close together each one must be removed and cleaned causing great loss of time.

I have discovered that by locating a cleaning brush under the bottom screws so that it will be in contact with the bottom faces of the fallers, as they move, not only the bottom but the entire faller will be cleaned.

It appears that the longer of the shorter fibers being caught by the brush, wipe around and carry with them the short fibers and the dirt so that all are caught and removed.

Moreover as the fiber moves faster than the faller pins, most of the dust or dirt which comprises some 90° of the waste is caught on what might be called the back side of each faller and if this back side is constantly kept clean and the bottom is also kept clean as by my device, it does not gum up but seems to slip down and around the bottom, on to the brush where it accumulates on what

might be called the front side from which it drops off by gravity on to the ground. By so keeping the faller body always clean instead of removing the fallers for cleaning twice a week as is customary I find if my fallers are removed every three months and carefully cleaned or polished it is sufficient.

I prefer to make my brush of a sufficient size to span the space between at least two fallers so that it cannot slip up and jam between them.

I also prefer to provide a suitable balanced or elastic support for the brush to take up wear and to allow it to be instantly pushed down and out of the way for inspection, etc.

In the drawings, Fig. 1 is an elevation from the front or side end of a gill box of the usual type, parts being broken away so as to make the construction clear.

Fig. 2 is a view from the right of Fig. 1, omitting various parts for clearness, and showing others diagrammatically.

Fig. 3 is a section through guide screw 32.

In the drawings, A is the frame of a gill box and B and C are the top screws while D and F are the bottom screws.

10, 10 and 11, 11 are guides for the fallers M, M, each of which has ordinarily four faces, 1 and 2 being the back and front faces, 5 being the top face and 3 the bottom face. From the top face of each faller project one or more rows of pins 4, 4.

As shown in Fig. 2, these fallers M, M, travel in the direction of the arrow along with the stock G which passes between a front roller 20 and an apron 22, carried by roller 21 and then are forced down by cams of well known construction, but not shown in detail, to and between the bottom screws F and D, during which they travel in the direction of the bottom arrow until they are again raised by other cams between the top screws B and C.

The bracket 46 is fastened to the frame by a bolt 7 and carries at one end an open bearing 45 in which is a pivot 44 for a yoke 42, through which passes the brush support K which includes a shank 41 adjustable in yoke 42 by means of a screw 43,

and having at one end 49 an adjustable weight 47, whose location is determined by adjusting screw 48.

The other end is bent at 40 to carry a brush socket 31 held on by means of guide screw 32 and fastened to brush H by screws 33. Screw 32 enters loosely slot 35 in end 40.

This brush H is of such distance from front to back that it spans the space between at least two fallers M as they travel, and is so located that as they travel along the screws, the bottom face of each faller is engaged and cleaned.

By using an open bearing 45, the whole brush and its support can instantly be removed for cleaning, adjusting or for any other purpose.

I prefer to make slot 35 in end 40 a little longer crosswise and lengthwise than guide screw 32 to allow brush H to press evenly against the whole bottom face of each faller.

I claim:

1. The combination in a gill box having means to cause the stock to move horizontally in a given direction and having top screws and bottom screws together with fallers each of substantially rectangular cross section and each having pins projecting from its top face and having a flat bottom face, said fallers being caused to move along and between the top screws whereby the pins penetrate the stock and to move in the same direction therewith but at a slower speed and which fallers then descend and move each in an upright position in the opposite direction between the bottom screws; of a flat faced brush positioned under the bottom screws at a position nearer the lifting than the receiving end thereof, said brush being of such size as to span the space between two fallers with the bottom faces of which it engages while said fallers are supported by said bottom screws; a brush socket medially fastened to the bottom of said brush and having a cylindrical hole and a guide screw which enters said hole; a bracket fixed to the frame of the gill box having at the top an open bearing; a yoke having a pivot which rests in said open bearing; a brush support which passes adjustably through said yoke and which at one end enters the socket hole and has a transverse slot into which said guide screw enters and at the other end has an adjustable weight whereby the brush is held yieldingly in contact with the bottom faces of said fallers as they move along the bottom screws.

2. The combination in a gill box having means to cause the stock to move horizontally in a given direction and having top screws and bottom screws together with fallers each of substantially rectangular cross section and each having pins projecting from its top face and having a flat bottom face, said fallers being caused to move along and between the top screws whereby the pins penetrate the stock and to move in the same direc-

tion therewith but at a slower speed and which fallers then descend and move each in an upright position in the opposite direction between the bottom screws; of a flat faced brush positioned under the bottom screws of such size as to span the space between two fallers with the bottom faces of which it engages while said fallers are supported by said bottom screws; and means to yieldingly hold said brush in contact with the bottom faces of said fallers as they move along the bottom screws.

3. The combination in a gill box having means to cause the stock to move horizontally in a given direction and having top screws and bottom screws together with fallers each of substantially rectangular cross section and each having pins projecting from its top face and having a flat bottom face, said fallers being caused to move along and between the top screws whereby the pins penetrate the stock and to move in the same direction therewith but at a slower speed and which fallers then descend and move each in an upright position in the opposite direction between the bottom screws; of a flat faced brush positioned under the bottom screws at a position nearer the lifting than the receiving end thereof, said brush being of such size as to span the space between two fallers with the bottom faces of which it engages while said fallers are supported by said bottom screws; and means to yieldingly hold said brush in contact with the bottom faces of said fallers as they move along the bottom screws.
